L. T. MURRAH

OSCILLATING FIGURE FOR AUTOMOBILES

Filed Dec. 30, 1922

UNITED STATES PATENT OFFICE.

LOUIE T. MURRAH, OF DALLAS, TEXAS.

OSCILLATING FIGURE FOR AUTOMOBILES.

Application filed December 30, 1922. Serial No. 610,083.

To all whom it may concern:

Be it known that I, LOUIE T. MURRAH, citizen of the United States of America, residing at Dallas, in the county of Dallas and State of Texas, have invented certain new and useful Improvements in Oscillating Figures for Automobiles, of which the following is a specification.

This invention relates to new and useful 10 improvements in oscillating figures for motor vehicles.

The object of the invention is to provide means for mounting a figure or simulation of an animal on the front end of an automobile in connection with a wind wheel, in such a manner that the revolution of the wheel imparts an oscillating movement to the figure.

A particular object is to provide an improved form of support together with a rotating crank co-operating with an oscillating arm for imparting a galloping movement to a figure carried by the crank and arm.

25 A construction designed to carry out the invention will be hereinafter described together with other novel features of the invention.

The invention will be more readily understood from a reading of the following specification and by reference to the following drawings, in which an example of the invention is shown and wherein:

Fig. 1 is a front elevation of a device 35 constructed in accordance with my invention,

Fig. 2 is a side elevation of the same,

Fig. 3 is a plan view, and

Fig. 4 is a detail of the swinging arm.

40 In the drawings the numeral 10 designates a U-shaped upright bracket which is fastened on the end of a supporting arm 11 parallel therewith. The arm is twisted upon itself to provide an arcuate clamp member 12 which has an ear 13 at its outer end. An arcuate keeper 14 conforming to the member 12 is provided with an ear 15 at one end and a similar ear 16 at the opposite end. The parts 12 and 14 are adapted to clamp 45 around the filling collar of a radiator and the ear 15 is fastened to the ear 13 by a bolt 17, while the ear 16 is fastened to the member 12 by a bolt 18 passing thru the latter.

The arm 11 and bracket 10 are thus supported in advance of the radiator cap. In 55 the upper end of the bracket is journaled a

crank shaft 19 which has its forward end extending thru the front leg of the bracket. A wind wheel 20 is fastened on the forward end of shaft and has its blades so bent as to 60 revolve the wheel when impinged by air currents. The rear end of the shaft projects thru the rear leg of the bracket and is provided with a crank 21.

A rigid bracket arm 22 extends laterally 65 from the lower portion of the rear leg of the bracket and has its outer end bent upon itself to form a bearing member 23. An upright swinging arm 24 has its lower end forwardly and engaged in the member 23, the 70 forward extremity being upset to prevent withdrawal from said member. The upper end of the arm is bent rearwardly and pivoted in a figure 25. The figure is provided with a flanged bearing sleeve 26 in 75 which the upper end of the arm is received and the extremity of the arm is upset to confine it in the sleeve.

The figure has a second sleeve 27 spaced laterally from the sleeve 26 and receiving 80 the crank shaft 21, which has its extremity upset to confine the sleeve thereon. It will be seen that the figure is wholly supported on the crank 21 and the arm 24. In the present instance the figure is that of a donkey, 85 but it may be a camel, manikin or any other figure or animal. The figure may also be hollow or flat, the latter being illustrated.

The crank supports the donkey over its hind legs and the arm is pivoted to it just 90 rearwardly of the fore legs. The crank is considerably shorter than the arm and thus while the crank is rotated the arm is merely swung or rocked. This will cause the rear end of the figure to move in a circular 95 orbit, while the forward portion moves thru an elliptical path, the combined movements simulating a galloping or bucking motion. The bucking motion is more pronounced when the wind wheel is revolved at a high 100 rate of speed.

The peculiar motion is obtained by reason of the unequal lengths of the crank and arm and their spacing, together with the mounting of the figure entirely upon the same. 105

Various changes in the size and shape of the parts as well as modifications may be made within the scope of the appended claims.

What I claim,

1. In an oscillating figure, a support 110 comprising a vertical member having an arm support at one side thereof, a crank

shaft pivoted upon the vertical member and provided with a wind wheel, a non-articulated figure at one side of said support having its body pivoted to the crank shaft to receive a rotary movement therefrom at one end, and a swinging arm upon the arm support spaced from said shaft and pivoted to the body of the figure for imparting an oscillating movement to the opposite end of the figure.

2. In an oscillating figure, a vertical support having a lateral arm intermediate its ends, a crank shaft mounted at the upper end of the vertical support and provided with a wind wheel, a non-articulated figure at one side of said support having its body directly connected to the crank shaft, and a swinging arm of greater length than the crank of said shaft and pivoted to the lateral arm of said support and to the body

of said figure, whereby a rotary movement is imparted to one end of the figure while the opposite end oscillates.

3. In an oscillating figure, a supporting bracket having vertical and horizontal members and a clamp for attachment to an automobile radiator, a crank shaft mounted in the upper end of the vertical member, a wind wheel secured to one end of said shaft, a non-articulated figure in the rear of the bracket having its body pivoted directly upon the crank shaft to receive a rotary movement therefrom, and a swinging arm pivoted upon the horizontal member and having its upper end pivotally connected to the body of the figure to permit an oscillatory movement thereof at a point spaced laterally from the crank shaft.

In testimony whereof I affix my signature.
LOUIE T. MURRAH.
